INVENTOR

SAMUEL W. BURCHARD

By Higdon & Langdon Atty's.

UNITED STATES PATENT OFFICE.

SAMUEL W. BURCHARD, OF ST. LOUIS, MISSOURI.

CATTLE-GUARD.

1,221,286.

Specification of Letters Patent. Patented Apr. 3, 1917.

Application filed May 19, 1914. Serial No. 839,650.

To all whom it may concern:

Be it known that I, SAMUEL W. BURCHARD, a citizen of the United States, and resident of St. Louis, Missouri, have invented 5 certain new and useful Improvements in Cattle-Guards, of which the following is a specification containing a full, clear, and exact description, reference being had to the accompanying drawings, forming a part hereof.

10 My invention relates to improvements in cattle guards, of that class known as surface guards, in which a plurality of bars are disposed longitudinally of the rails to present an uninviting surface for animals to walk 15 over.

The primary object of my improvements is to construct a surface guard of a number of bars whose sectional characteristics present tread faces bearing such angular relationships with each other as to cause lateral deflections of feet or hoofs without presenting pockets or traps in which the feet or hoofs may be caught and held, particular regard being had to produce a surface over 25 which animals may pass, if sufficiently urged.

A further object of my improvements is to combine with the faces having the angular relationship referred to, teeth, barbs or the like which will in no sense preclude 30 passing of animals over the guard, but will if engaged at the time of the animal's first step on the guard cause the animal to turn back and not attempt further passing over the guard.

35 I attain these objects by the guard fully set forth in the following specification, pointed out in my claim and illustrated in the accompanying drawings, in which:

Figure 1 shows in elevation a guard embodying my invention;

Fig. 2 shows in end elevation my improved guard;

Fig. 3 is a detail perspective of a portion of one of the bars; and

45 Fig. 4 is an enlarged detail transverse sectional elevation of a complete bar.

Referring by numerals to the accompanying drawings:

50 5 designates the rails and 6 the ties or sleepers of an ordinary trackway.

55 7 designates the bars of my improved guard, each of which has at intervals throughout its length the vertical openings 8 arranged to receive drift-pins 9 which will hold the bars against longitudinal or lateral shifting or displacement, yet which will

readily permit of the bars being removed from the trackway for purposes of repair thereto.

Each of the bars 7 comprises a plane, 60 horizontal base surface 10; a plane, vertical side face 11, which is at right angles to the base 10; a plane, upper, inclined face 12, extending between the side face 11 to a point beyond the median line of the bar; a relatively short, inclined upper face 13 leading downwardly from the upper end of the face 12 at an oblique angle relative to the face 12; and a plane, side face 14 extending from the base 10 to the lower end of the shortest 65 upper inclined face 13, which last mentioned side face bears an oblique angular relationship to both the base surface and the short inclined upper face.

Each end of each bar is beveled, as shown, 70 in order that loose-hanging parts on rolling stock will not catch the bars in passing therover.

In arranging the bars with relation to each other, care should be taken to space them 80 so that the apexes are separated distances greater than the average widths of horses' and cattle's hoofs, and so that there will be ventilating space between adjacent side faces of the bars.

85 By reason of the upper face of one bar having an angle differing from the angle of the upper face of an adjacent bar, a hoof placed on both faces will be deflected by the face having the greatest angle.

90 In this particular I distinguish from the guards constructed of bars whose faces are all of like angle and over which bars hooved animals will pass with comparatively "secure footing" by treading in the "troughs", 95 with their hoofs resting on each side of the "troughs."

100 In the preferred construction of my improved bar I employ a metallic shell such as 15, which I fill with reinforced concrete or the like, as shown at 16 in Fig. 4, wherein the shells offer faces over which the hoofs will slip with a minimum of resistance, and hence present a face upon which a hooved animal will tread with great caution, while 105 the reinforced body of concrete lends rigidity to the shell.

110 In order to inflict slight injury or punishment to animals which persist in passing over the guard whereby to deter them from making subsequent passages, I arrange the longitudinal rows of barbs or teeth 17, 18 and

19, which as shown in Fig. 4, are placed at such points on the bars as to coöperate most advantageously with the various tread faces of the bars.

5 The barbs 17 are arranged to prick or scratch the ankles or legs of animals which have trod upon the faces 12, especially on the bars lying to the right of the rails and the left hand side bar outside of the track.

10 The barbs 18 are arranged to prick or scratch the angles of hoofs deflected from the faces 13 and the barbs 19 arranged to prick or scratch the ankles of hoofs deflected from the faces 12.

15 Having thus described my invention, what I claim as new therein and desire to secure by Letters Patent of the United States therefor, is:

In a cattle guard, a solid body of bar for-

mation, having a plane horizontal bottom 20 surface, an inclined plane upper surface leading from the bottom surface and terminating at a point to one side of the transverse median line of the body, a second plane upper surface leading from said point 25 in a direction opposed to and at an angle different from the first mentioned upper surface and terminating at a point overhanging the bottom surface and a plane surface inclining from said overhanging point 30 to the bottom surface.

In testimony whereof, I have signed my name to this specification, in presence of two subscribing witnesses.

SAMUEL W. BURCHARD.

Witnesses:

E. L. WALLACE,
EDWARD E. LONGAN.
